UNITED STATES PATENT OFFICE.

CHARLES A. HUFFMASTER, OF SAN LEANDRO, CALIFORNIA.

STEAM-DOME AND BREECHING.

SPECIFICATION forming part of Letters Patent No. 770,465, dated September 20, 1904.

Application filed December 31, 1903. Serial No. 187,258. (No model.)

To all whom it may concern:

Be it known that I, CHARLES A. HUFFMASTER, a citizen of the United States, residing at San Leandro, in the county of Alameda and 5 State of California, have invented new and useful Improvements in Steam-Domes and Breechings, of which the following is a specification.

My invention relates to improvements in 10 steam-boilers.

It consists especially in the novel arrangement of the steam-dome and an internally-disposed breeching and connections whereby the hot products of combustion after passing 15 through the boiler-flues are carried through the breeching to the stack, so as to heat the steam contained within the dome, while the effect of the surrounding steam is to prevent the burning out of the breeching.

20 My invention also comprises a means for diverting the upwardly-moving gases and throwing them more directly against the interior surface of the breeching before said gases escape from the stack, and it also comprises details of construction, which will be 25 more fully explained by reference to the accompanying drawings, in which—

Figure 1 is an elevation and partial section of a vertical flue-boiler, showing my invention. Fig. 2 shows the application to an inclined water-tube boiler. Fig. 3 is a section of the exhaust-pipe joint.

It is the object of my invention to more thoroughly economize the hot products as they 35 escape from the furnace through the boiler-tubes and to the chimney or smoke-stack, and I effect it by the formation of a peculiarly-shaped breeching within the steam-dome and by bringing the hot products of combustion 40 into contact with the breeching in such a manner as to superheat the steam inclosed in the surrounding dome.

In the accompanying drawings, A represents a boiler having a furnace of any suitable 45 description and flues or tubes through which the products of combustion pass and by which the water surrounding these tubes is heated.

I have here illustrated my invention as applied to a vertical or upright boiler having

the tubes 2, and above the top of that portion 50 of the boiler occupied by the tubes I have shown a dome, as at 3. This dome receives the steam, and from it the steam is drawn for such uses as may be required. Within the dome is a conical breeching, as at 4, having 55 its base or largest portion bolted or otherwise secured around the lower part of the dome and converging thence upwardly to a point where it connects with a smoke-stack, as at 4^a. This construction leaves a space 5 surrounding the conical breeching, and this space receives the steam generated in the main portion of the boiler, the steam being transmitted into this dome by means of a pipe or pipes, 60 as at 6. The products of combustion passing 65 through the tubes in the boiler and upwardly, through the breeching converge toward the smoke-stack, and at the same time these hot products impinge against the side of the breeching, thus imparting their heat to the steam 70 within the dome, superheating it. At the same time the effect of this surrounding steam will be to prevent the breeching from being so highly heated as to burn out or be destroyed. In order to more fully effect the object desired, 75 I have shown a cone 7 located near the apex of the conical breeching and properly supported by rods or stays, as at 8. The cone converges downwardly, having its mouth presented toward the chimney, and this cone will 80 divert the rising products of combustion and insure their striking against the interior of the breeching before they escape through the chimney, as they will afterward do by reason of their lightness. The steam-space of the 85 dome may have a suitable pipe connection, as at 10, with a union 11, so that it can be disconnected at will, and the dome and breeching may be removed whenever it is necessary to 90 reach the head or flue sheet of the main portion of the boiler.

The exhaust-pipe 12 from the engine enters the smoke-stack, and its discharge therein assists the draft. The smoke-stack is hinged at 13, so as to be turned down toward a horizontal position when desired, and segments are cut out of the side at the bottom and in the corresponding meeting edge to admit the

exhaust-pipe, and this allows the stack to be opened or closed without disturbing the exhaust-pipe.

If it is desired to remove the dome and breeching, it will be necessary to turn the exhaust-pipe out of the way, and this is effected by means of a joint, as shown at 14, which while turnable is also steam-tight.

I have heretofore described my invention as applied to upright boilers with heat-flues passing through the water-space of the boiler; but it will be manifest that it is equally applicable to what are known as "water-tube" boilers. Fig. 2 shows the application to a boiler of that class.

Having thus described my invention, what I claim, and desire to secure by Letters Patent, is—

1. The combination with a boiler, its furnace, and the flues passing therethrough, of a dome located above the flues, a conical interior wall or breeching having its base or largest portion secured directly around the lower part of the dome said breeching forming an exterior closed steam-space within the dome, said breeching having its upper end extending through the dome and secured approximately at the point where the dome is connected with the smoke-stack, so that the escaping products

of combustion impinge against the breeching before escaping from the stack.

2. The combination with a boiler having a heating-furnace, of a steam dome or extension located above the tubes, a conical breeching fixed above the tubes convergent toward the center and connected with a smoke-stack, said breeching forming an annular steam-chamber between itself and the outer wall of the dome, and an inverted cone fixed approximately at the junction of the breeching with the smoke-stack.

3. The combination with a boiler and its furnace, of a removable steam-dome located above the tubes, a convergent conical breeching fixed within the steam-dome and forming therewith an annular steam-space exterior to itself, connections between the main boiler and said steam-space, an inverted cone fixed at the junction of the breeching and the smoke-stack and removable jointed conducting-pipes connecting with the steam-space of the dome.

In testimony whereof I have hereunto set my hand in presence of two subscribing witnesses.

CHARLES A. HUFFMASTER.
